US00D641408S

(12) **United States Design Patent**
Zhang

(10) **Patent No.:** **US D641,408 S**
(45) **Date of Patent:** **** Jul. 12, 2011**

(54) **PEN**

(75) Inventor: **Youbin Zhang**, Ningbo (CN)

(73) Assignee: **Beifa Group Co., Ltd.**, Ningbo (CN)

(**) Term: **14 Years**

(21) Appl. No.: **29/365,887**

(22) Filed: **Jul. 16, 2010**

(30) **Foreign Application Priority Data**

Jan. 17, 2010 (CN) 2010 3 0001979

(51) **LOC (9) Cl.** **19-06**

(52) **U.S. Cl.** **D19/50**

(58) **Field of Classification Search** D19/35,
D19/36, 41-51, 54-58; 24/11 F, 11 P, 11 R;
